UNITED STATES PATENT OFFICE.

WILLIAM WALLACE, OF NEW YORK, N. Y.

WINDOW-SASH.

SPECIFICATION forming part of Letters Patent No. 416,198, dated December 3, 1889.

Application filed September 14, 1888. Serial No. 285,431. (No model.)

To all whom it may concern:

Be it known that I, WILLIAM WALLACE, of the city, county, and State of New York, have invented a new and useful Improvement in 5 Window-Sashes, which improvement is fully set forth in the following specification and accompanying drawings, in which—

Figure 1 is a vertical front projection or view, partly in section, of a sash containing 10 my improvement. Fig. 2 is a cross-section of the same. Fig. 3 is a vertical side projection or view of a longitudinal section of same. Fig. 4 is a vertical section of same, showing adjustable parting-strip E and metal facing 15 of pulley-stiles F. Fig. 5 is a horizontal or cross-section of the metal pulley-stiles F and adjustable parting-strip E. Fig. 6 is a perspective sketch of the metal bearer, C showing tongue and D showing socket.

20 The object of my invention is to furnish a device by which window-sashes may be made water, air, and dust tight.

In the drawings, the sashes A are the ordinary window-sash, with the addition of the 25 loose stiles B. These loose stiles are rabbeded so as to fit the rabbet in the stiles of the sashes, as shown in Fig. 2 at S. The arrangement of these loose stiles B prevents air, dust, or water from coming to the inside 30 of the window. The loose stiles B have two or more bearers C, (shown on Figs. 1 and 6,) each with a tongue of iron or other metal which fits into the iron or other metal socket D, Figs. 1 and 5. Each sash has two or more 35 of these metal sockets D, which are screwed fast to the stiles of the sashes and correspond with the tongues and bearers C of the loose stiles. When the sash is placed in position between the loose stiles B, it and the loose 40 stiles form substantially but one stile.

An adjustable parting-strip E runs from the bottom to the top of the window-frame and fits into the grooves of the loose stiles B and between the tongues of the pulley-stiles F. 45 This parting-strip is not made fast to either the frame or the loose stiles or the pulley-stiles, but is kept in position by the loose stiles. The pulley-stiles F are faced with iron or other metal, and have two projecting 50 tongues, which allow the adjustable parting-strip E to move freely without regard to the state of the weather. The loose stiles B and

the adjustable parting-strip E are placed in position together and prevent air, water, or dust from entering from outside around the 55 window.

The meeting-rails M of both sashes, Fig. 3, are connected by means of an adjustable hinged and tongued weather-strip N. The outside edge of this weather-strip N is secured 60 by hinges to the lower meeting-rail of the upper sash, allowing the weather-strip to turn up freely. The tongue O fits into a groove T in the meeting-rail M at the top of the lower sash and runs the whole width of the window. 65 The weather-strip has also a folding arm P, containing a small opening Q near the end, arranged to fit over a revolving cap R on the inside of the meeting-rail M of the lower sash. This weather-strip, with its tongue O fitting 70 into the groove T when closed, effectually prevents air, water, or dust entering through the space between the meeting-rails of the two sashes.

In order to open the window, it is only necessary to give the revolving cap R a half-turn 75 and lift the arm P, and with it the weather-strip N, which turns back. The sashes can then be easily raised and lowered.

G shows the sash-weight pulleys; H, the 80 sash-weight chain or cord; I, Fig. 1, the sash-weight itself, and K K braces or stops, one of which is hung at the center of each of the four stop-beads L. These braces fit over the top of the loose stiles B and prevent their sliding 85 upward.

In case the adjustable parting-strip E should become worn, and it becomes necessary to replace it, both sashes may be removed. In order so to do, turn forward the braces K K and 90 the sashes can readily be taken out and put aside. Then remove the loose stile B and the old adjustable parting-strip E, which replace with a new one, and put parts taken out in former position. In case it should become necessary to get at the sash-weight for any purpose, the same process may be gone through, with the addition, after removing the loose stiles B and adjustable parting-strip E, of removing the screws in the lower half of the 100 pulley-stiles F, by which they are screwed to the frames. Then remove the pulley-stiles and take out the sash-weight. The pulley-stiles are faced with iron, brass, or other

metal. When they are placed in position, this metal makes a continuous facing the whole height of the window and prevents shrinking in the pulley-stiles, thus keeping the sash 5 always in good working order.

The paint on the windows is not disfigured by any of the above operations.

Having described my invention, what I claim as new, and desire to secure by Letters Patent, is—

The combination of a window-frame, an up-

per sash, and a lower sash having a groove T in its meeting-rail, of the adjustable parting-strip E, the loose stiles B, the metal-faced pulley-stiles F, the braces K K, and the 15 weather-strip N, with tongue O, folding arm, and opening and revolving cap, all and each of same substantially as shown and described.

WILLIAM WALLACE.
